UNITED STATES PATENT OFFICE.

ADOLPH BALLENBERG, OF NEW YORK, N. Y.

GLIDER FOR FURNITURE-LEGS.

1,230,836.

Specification of Letters Patent. Patented June 26, 1917.

Application filed October 14, 1915. Serial No. 55,775.

To all whom it may concern:

Be it known that I, ADOLPH BALLENBERG, a citizen of the United States, and residing at New York, in the county of New York 5 and State of New York, have invented certain new and useful Improvements in Gliders for Furniture-Legs, of which the following is a specification, such as will enable those skilled in the art to which it appertains to make and use the same.

This invention relates to gliders for the legs of furniture and other heavy articles, and particularly to what are known as metallic and hollow legs, and the object thereof 15 is to provide an improved glider or gliders of this class which may serve as gliders only, or be quickly and easily changed to serve as a support or supports for casters; and with this and other objects in view the invention 20 consists in a device or devices of the class specified, constructed as hereinafter described and claimed.

The invention is fully disclosed in the following specification, of which the accompanying drawing forms a part, in which the separate parts of my improvement are designated by suitable reference characters in each of the views, and in which:—

Figure 1 is a corner view in elevation of 30 the bottom of the leg of an article of furniture provided with my improvement;

Fig. 2 a section on the line 2—2 of Fig. 1; Fig. 3 a section on the line 3—3 of Fig. 2; Fig. 4 a section on the line 4—4 of Fig. 3; 35 Fig. 5 a plan view of the blank from which my improved glider is made;

Fig. 6 a view similar to Fig. 2 but showing my glider used as an attachment for a caster; and,

Fig. 7 a plan view of a blank from which the glider member shown in Fig. 6 is made.

In the drawing forming part of this specification, I have shown at *a* the bottom part of a leg of a heavy article of furniture or 45 other article composed of angle iron, said leg being angular, or approximately so, in cross section and, in the practice of my invention, as shown in Figs. 1 to 5 inclusive, I provide an attachment *b* adapted to serve

50 as a glider and which is made from a blank *b*² shown in Fig. 5, said blank comprising a body part *b*³ substantially rectangular in form and provided at one side edge with a foldable extension *b*⁴ which is also approximately rectangular in form, and at the op-

posite side edge with a foldable extension *b*⁵ which is triangular in form.

The blank *b*² is folded along the lines *b*⁶ and the double lines *b*⁷ to form the glider attachment *b* and the main part *b*³ of the blank forms the back *b*⁸ of the attachment, while the rectangular side extension *b*⁴, or the main central part *b*⁹ thereof forms the bottom *b*¹⁰ of the attachment, and the triangular corner portions *b*¹¹ of the part *b*⁴ 65 of the blank form triangular side clamps *b*¹² of the attachment, and the triangular extension *b*⁵ at one side of the body portion *b*³ of the blank forms the top member *b*¹³ of the attachment which fits in, and transversely of, the angle of the leg *a*.

The double score lines *b*⁷ in the angle of the part *b*⁴ of the blank are for the purpose of forming transverse beads *b*¹⁴ at the base of the triangular spring clamp members *b*¹², 75 and the object of which is to reinforce said clamp members and give them greater spring action and make them more efficient in use.

When constructed in this manner my improved gliding attachment may be connected with the leg by simply forcing it upwardly 80 into the bottom thereof in which operation the top member *b*⁵ enters the leg, and said clamp members *b*¹² and the top portion *b*¹³ securely clamp and hold the attachment to 85 the leg.

The central part *b*⁴ of the blank which forms the bottom *b*¹⁰ of the attachment is provided with a semi-circular, or approximately semi-circular depression *b*¹⁵ which 90 forms the bearing or glider proper of the attachment and which operates in the same manner as other devices of this class.

It must be understood that my invention is not limited to a leg of the form in cross section herein shown and described but may be applied to any metallic hollow leg either cylindrical, square or octagonal in cross section, all that is necessary being that the said attachment be so formed as 100 to be capable of being forced upwardly into or onto the leg and be provided with spring clamp devices which hold it in connection therewith.

In Fig. 6, I have shown my improved attachment used for the purpose of securing a caster *c* to the leg *a*, and the attachment in this case is made from the blank shown in Fig. 7, and this blank differs from the blank shown in Fig. 5 only in that the 110

triangular side extension b^5 of the body portion b^3 of said blank is provided with an aperture b^{16} through which the pintle c^2 of the caster passes. In this form of construction, the bottom bearing member b^{17} formed by the depression b^{15} in the bottom of the attachment is pierced as shown at b^{18} to form an aperture through which the pintle is also passed, and all that is necessary 10 is to pass the pintle of the caster up through the apertures b^{18} and b^{16} and rivet the head of the pintle as shown at c^3 , and with this construction the glider bearing b^{17} forms a bearing which rests on the central top portion c^4 of the yoke c^6 of the caster and rotates thereon in the operation of moving the article of furniture or other article from one point to another, and to facilitate this 15 operation the outer edge portion of the aperture b^{18} is rounded as shown at b^{19} , and my improved gliding attachment may in this way be made to serve as a safe and secure attachment for a caster and one which may be quickly and easily applied and which is held 20 in place by spring clamp devices only, and in which the caster, or its pintle c^2 is free to rotate with a minimum amount of friction and may also serve as a glider, if desired, the rounding edges b^{19} of the aperture b^{18} permitting the attachment to move freely over 25 the floor.

Having fully described my invention, what I claim as new and desire to secure by Letters Patent, is:—

35 1. A gliding attachment for an angular leg of an article of furniture, said attachment being formed from sheet metal and consisting of a bottom plate approximately triangular in form and provided at one side 40 edge with an upwardly directed plate having a top portion which fits in the angle of the leg and at the other side edge portions

thereof with upwardly directed spring clamping members which engage the outer surfaces of side portions of the leg and 45 which are provided at the bottom thereof with outwardly directed transverse bends or beads, said bottom plate being also provided with a central convex bearing.

2. A gliding attachment for use in connection with an angular support, said attachment being formed from sheet metal and consisting of a bottom plate on which the support rests, and a back plate extending upwardly from the bottom plate and 55 being provided with a top plate which fits transversely in the angle of the support, said bottom plate being provided with upwardly directed spring clamp members which engage the outer surface of the sides 60 of the support, and said bottom plate being also provided with a convex bearing member.

3. A device of the class described adapted to be used in connection with an angular support, said device being formed from sheet metal and consisting of a bottom plate on which the support rests, a back plate and a top plate, said bottom plate being also provided with upwardly directed spring 70 clamping members which engage the outer surfaces of the sides of the support, the bottom plate being provided with a convex bearing member and said top and bottom plates being provided with apertures.

In testimony that I claim the foregoing as my invention I have signed my name in presence of the subscribing witnesses this eleventh day of October, 1916.

ADOLPH BALLENBERG.
